PROCESS FOR THE PURIFICATION OF
PYRETHRIN CONCENTRATES

Herbert L. J. Haller, Washington, D. C., and
Frederick B. La Forge, Clarendon, Va., assignors
to Henry A. Wallace, Secretary of Agriculture
of the United States of America

No Drawing. Application February 18, 1936,
Serial No. 64,516

4 Claims. (Cl. 167—24)

(Granted under the act of March 3, 1883, as
amended April 30, 1928; 370 O. G. 757)

This application is made under the act of
March 3, 1883, as amended by the act of April
30, 1928, and the invention herein described, if
patented, may be manufactured and used by or
5 for the Government for governmental purposes
without the payment to us of any royalty thereon.

This invention relates to the preparation of
concentrates with high content of the active con-
stituents of pyrethrum flowers. It represents a
10 further development of the invention described
in our copending patent application, Serial No.
40,288, filed September 12, 1935, and supplements
the process therein described.

Although the process described in the applica-
15 tion referred to accomplishes the removal of fats,
waxes and other nontoxic byproducts from an
oleoresin obtained on extraction of pyrethrum
flowers with petroleum ether and generally re-
suits in a material with a content of 60-65 per
20 cent of total active principles, the product ob-
tained by this procedure still contains several per
cent of acids of various kinds. For some purposes
it is desirable to produce a concentrate of still
higher pyrethrin content and which is free from
25 acids.

Since the pyrethrins are esters with neutral
properties, it is obvious that a solution containing
them, together with other materials with acid
30 properties in a suitable solvent, could be freed
from the acid materials by treatment with an
aqueous alkali solution in which the latter are
soluble.

It is however practically not possible to carry
35 out this operation because the alkali salts of the
acids are of the nature of soaps and as such form
emulsions in which the solution containing the
pyrethrins is occluded and such emulsions sep-
arate only partly, even on very long standing.

The problem resolves itself into finding a suit-
40 able solvent capable of dissolving the pyrethrins
but in which the soaps are not soluble and which
does not form emulsions difficult to break. At the
same time the nature of the solvent must be such
45 as to permit its removal from the pyrethrin by
physical or chemical means without affecting the
pyrethrins.

A liquid having these desired properties is
aniline oil.

In the practice of this invention, the partly
50 purified pyrethrin concentrate prepared as de-
scribed in application, Serial No. 40,288, is dis-
solved in a suitable quantity of aniline, and to
this solution is added a concentrated aqueous
55 solution of potassium carbonate. The two solu-
tions which do not mix are agitated together to

insure intimate contact for several hours. During
this process the temperature is kept at about -10°
C. by outside cooling to prevent any saponifica-
tion of the pyrethrins. The reaction having been
completed, the aniline solution containing the 5
pyrethrins is separated mechanically from the
aqueous solution containing the soaps resulting
from the neutralization of the fatty acids. The
pyrethrins are then separated from the aniline
by dissolving the latter in an aqueous solution of 10
a mineral acid maintained at a low temperature
by means of ice. The pyrethrins being insoluble
are separated from the acid solution by dissolving
them in any low boiling solvent immiscible with
water, such as petroleum ether, which solvent is 15
subsequently removed from the pyrethrins by
evaporation.

As a specific instance of the application of these
processes the following more detailed description
is presented. 20

About 140 gms. of pyrethrin concentrate ob-
tained by the process described in application
Serial No. 40,288 are dissolved in 400 cc. of fresh-
ly distilled aniline and the solution is agitated
for 8 hours at -10° C. with an aqueous solution 25
of 140 gms. of potassium carbonate in 600 cc. of
water. At the end of the time specified, the two
solutions are allowed to separate and the lower
aqueous soap solution is drawn off.

The aniline solution is washed by agitation 30
with an aqueous carbonate solution and is then
allowed to run slowly onto a mixture of 400 cc.
of concentrated hydrochloric acid plus 400 gms.
of cracked ice with constant stirring of the mix-
ture. The pyrethrins which remain undissolved 35
are extracted with petroleum ether. The pe-
troleum ether solution is washed and dried after
which the solvent is removed by evaporation leav-
ing the purified pyrethrins in the form of a light
yellow oil. The yield of material containing 70 40
per cent of total pyrethrins is about 90 gms.

Having described our invention we claim:

1. The process of removing fatty acids from a
pyrethrin concentrate which comprises dissolving
the pyrethrin concentrate in aniline, treating 45
the aniline solution with an aqueous alkali solu-
tion, removing the aqueous alkaline solution and
separating the aniline from the pyrethrins by
means of a mineral acid.

2. The process of removing acid materials from 50
a pyrethrin concentrate previously freed from
fats and waxes which comprises agitating the
pyrethrin concentrate in aniline with an aqueous
solution of an alkaline carbonate, separating the
aniline solution from the aqueous solution me- 55

chanically and separating the pyrethrins from the aniline by means of a mineral acid.

3. The process of removing acid materials from a pyrethrin concentrate which comprises dissolving the pyrethrin concentrate in aniline, adding a concentrated aqueous solution of potassium carbonate, agitating the two combined solutions at -10° C. for several hours, separating the aniline solution mechanically from the aqueous alkaline solution, separating the pyrethrins by dissolving the aniline in an aqueous solution of a mineral acid at a low temperature, recovering the pyrethrins from the acid solution by dissolving them in a low boiling solvent immiscible with water and removing the solvent by evaporation.
4. The process of removing acid materials from

a pyrethrin concentrate which comprises dissolving the pyrethrin concentrate in aniline, adding an aqueous alkaline solution to the aniline solution, agitating the two combined solutions at a reduced temperature for several hours, separating the aniline solution mechanically from the alkaline solution, separating the pyrethrins from the aniline by dissolving the latter in an aqueous solution of a mineral acid maintained at a low temperature, separating the pyrethrins from the acid solution by dissolving them in a low boiling solvent immiscible with water and removing the solvent by evaporation.
